UNITED STATES PATENT OFFICE.

FRITHGOF BERGGREN, OF BROOKLYN, NEW YORK.

KEY-FASTENER.

1,235,098.

Specification of Letters Patent. Patented July 31, 1917.

Application filed August 30, 1916. Serial No. 117,692.

To all whom it may concern:

Be it known that I, FRITHGOF BERGGREN, a citizen of the United States of America, residing at New York city, borough of Brooklyn, in the county of Kings and State of New York, have invented certain new and useful Improvements in Key-Fasteners, of which the following is a specification.

This invention relates to an improved key fastener designed for fastening a key within its key-hole from one side of a door so as to prevent the key from being turned or pushed out to allow the insertion of a duplicate or skeleton key or the use of any instrument for picking the lock whereby forcible entry may be made to a room or building.

An object of the invention is to provide an improved key fastener which includes a shank for insertion in a key-hole and a pivot part designed to engage the bow of the key in a simple and secure manner whereby displacement of the key is obviated, while the device is so constructed as to obviate the necessity of employing keys, pins or set-screws to secure the device to a key or the bow thereof, thereby providing a device which can be conveniently carried in one's pocket and which will not be cumbersome, but which on the contrary, will occupy a minimum of space when not in use, while it can be applied and removed with celerity.

With the above objects and others in view, as will appear as the description proceeds, the invention comprises the various novel features of construction and arrangements of parts which will be more fully described hereinafter and set forth with particularity in the claims appended hereto.

Reference is had to the accompanying drawings forming a part of this application, in which like characters indicate the corresponding parts throughout the several views and wherein—

Figure 1 is a perspective view of one form of the improved key fastener showing a key in phantom with a fastener applied thereto.

Fig. 2 is a side elevation or edge view of a modification of the improved fastener.

Fig. 3 is a plan view showing the blanks from which the fastener is made.

Fig. 4 is a fragmentary side elevation showing a further modification of the fastener, and

Fig. 5 is a fragmentary side elevation of the fastener shown in Fig. 1.

As shown in Figs. 1 and 5, the improved fastener includes a shank 6 which is vertically disposed in reference to its edge portions and twisted as shown at 7 to provide a horizontal portion 8. The shank 6 is constructed of a blank section or strip of resilient metal such as steel and formed with an aperture 9 through the horizontal portion 8 and with a reduced extension or hinge tongue 10 at said horizontally positioned end.

Pivoted to the shank 6 at the horizontally positioned end 8 is an angular section 11 which has its end portion 12 disposed at right angles thereto, said end being bent toward the portion 8 and provided with an aperture 13 through which the reduced extension or tongue 10 is engaged and turned 75 or rolled to provide a hinge joint as shown so that the angular portion 10 is disposed in spaced parallel relation to the horizontal part 8, with the horizontal portion 8 substantially in alignment with the edge portion 14 and the pivoted part 11 spaced above the same. The free end of the part 11 is curved upwardly as shown at 15 so as to facilitate its manipulation on its pivot and the blank forming the part 11 is provided with a stamped out 85 tongue 16 bent downwardly from the free end of the part 11 on a reverse curve with the free end thereof serving as a catch to snap through the aperture 9 and secure the pivoted part 11 in the position shown in 90 Figs. 1 and 5. This is the position of the device when in use, the shank 6 being designed to enter the key-hole after the key 17 is inserted therein, in such a manner that the shank portion 6 prevents the turning of 95 the fastener within the key-hole while the bit of the key is horizontally positioned and thereby retained against rotation or turning in such a manner as to prevent its withdrawal. The bow 18 of the key is, therefore, positioned upon the horizontal portion 8 of the shank and when the pivoted part is moved into operative position parallel to the part 8, the spring catch 16 is forced through the bow of the key and the aperture 9, with 100 the walls of which it frictionally engages and in this manner the key is positively retained against displacement or turning, and the fastener cannot be removed from its engaged position by a person desiring to 110

105

make entry which is unscrupulous or otherwise, unless the fastener is removed from the inside.

In Fig. 2 of the drawings a modification 5 of the device is shown in which the construction is the same except that the horizontal portion 8' is in alignment with a medial line or the longitudinal axis of the shank 6 so that the key is held tensioned 10 when engaged by the fastener, the part 11' in this instance being positioned closer to the edge portion 14' than in the previously described form of the invention, in which the key is not held under tension as in the 15 present form.

In Fig. 4 of the drawings a still further modified form of the invention is shown in which the fastener is provided with a horizontal portion 19 forming a part of the 20 shank and which is bent upwardly as shown at 20 for pivotal connection of an upper part 21 thereto through the medium of a hinge joint 22, the part 20 forming a lug or hinge tongue which fits between spaced lugs 25 or tongues 23 at the end of the part 21, a pin being employed to pivotally connect the sections of the fastener.

From the foregoing description, taken in connection with the accompanying drawings, the advantages of the construction and of the method of operation will be readily apparent to those skilled in the art to which the invention appertains and while I describe the principle of operation of the 30 invention, together with the devices which I now consider to be the best embodiments thereof, I desire to have it understood that the devices shown are merely illustrative, and that such changes may be made when 35 desired as are within the scope of the device as claimed.

Having thus described my invention, what I claim as new and desire to secure by Letters Patent of the United States is:

- 45 1. A key fastener comprising a vertical shank portion twisted to provide a short horizontal portion; a section pivoted at the end of said horizontal portion and designed to move facewise toward and away from the 50 same; said horizontal portion having an aperture therethrough and a resilient catch integral with and projecting from the pivoted section to frictionally pass through the aperture, as and for the purposes set forth.
- 55 2. A key fastener comprising a resilient rectilinear section of a thin strip of spring metal vertically positioned to engage a key-

hole and twisted intermediate of its ends to provide a horizontal portion, a movable part pivoted to said horizontal portion and 60 having a stamped out tongue bent therefrom in a reverse curve, said horizontal portion having an aperture for frictional engagement of said tongue therethrough whereby to pass through the bow of a key held between said horizontal part and the pivoted part when so positioned in substantially parallel relation.

3. A key fastener comprising a narrow strip of resilient metal vertically positioned 70 and twisted to provide a short horizontal portion, said horizontal portion having a reduced extension at its end and a rectangular aperture therethrough, and an engaging strip having an end portion at right angles 75 thereto, said end portion having an aperture through which said reduced extension is engaged and turned to pivotally connect said parts to permit the engaging strip to be moved toward and away from the horizontal 80 part of the shank, said engaging strip having a spring catch to engage the aperture in said horizontal part at the outer edge wall thereof and an upwardly turned free end to facilitate its manipulation. 85

4. A key fastener comprising a narrow strip of resilient metal vertically positioned and twisted to provide a short horizontal portion, said horizontal portion having a reduced extension at its end and a rectangular 90 aperture therethrough, and an engaging strip having an end portion at right angles thereto, said end portion having an aperture through which said reduced extension is engaged and turned to pivotally connect said 95 parts to permit the engaging strip to be moved toward and away from the horizontal part of the shank, said engaging strip having a spring catch to engage the aperture in said horizontal part at the outer 100 edge wall thereof and an upwardly turned free end to facilitate its manipulation, the upper edge of the vertical portion of said strip being in horizontal alignment with the horizontal face portion of the horizontal 105 portion of the strip, as and for the purposes specified.

In testimony whereof I affix my signature in presence of two witnesses.

FRITHGOF BERGGREN.
